DESIGN FOR A DRESS

Abraham Greenspan, New York, N. Y.

Application February 1, 1936, Serial No. 60,940

Term of patent 3½ years

To all whom it may concern:

Be it known that I, Abraham Greenspan, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The design is characterized by a horizontal series of groups of graduated strips superimposed upon a netted background on the sleeves and front waist portion of the dress as shown.

I claim:

The ornamental design for a dress, substantially as shown, and described.

ABRAHAM GREENSPAN.
